TOP GUIDE FOR SLIDING PANEL CONSTRUCTION

Donald D. Foss, Van Nuys, Calif.

Application July 21, 1951, Serial No. 237,854

2 Claims. (Cl. 16—91)

1

This invention relates to a guide device for sliding panel construction, including doors, windows, and the like; and more particularly to a guide device adapted to be carried by the top portion of a slidable exterior or interior panel, etc.

Some prior proposed laterally slidable panel mountings included upwardly extending hangers attached to the top portion of a panel and provided with wheels carried at the top of each hanger for rolling engagement in a track extending above an opening to be closed. In other mountings, the panel was supported by wheels mounted in the bottom portion of the panel, the wheels tracking on a rail provided in the sill of the opening. In such latter mountings, the top portion of the panel was loosely and frictionally slidable within a downwardly facing slot or groove in the head of the frame of the opening. Both types of slidable mountings were unsuitable for exterior installations because of their relatively loose mountings, of vibration and rattling under windy conditions, and of the difficulty of maintaining tight and effective weather stripping around the opening in the frame. Weather tightness was especially difficult to secure in panel mountings having the top of the panel slidable in a groove. This invention provides a device for guiding the top portion of a panel so that effectiveness of weather stripping is maintained at the top of the opening while permitting smooth, easy slidability of a panel, door, window, etc.

Therefore, the primary object of this invention is to design and provide a top guide device for slidable panels, doors, windows, etc. which will preclude the objections mentioned above for use of sliding panel construction for exterior installations.

An object of this invention is to design and provide a guide device for sliding panel construction whereby a panel is maintained in virtually uniform spaced relation with respect to inner surfaces of the walls of a groove accommodating a portion of the panel while being opened or closed.

Another object of this invention is to design and provide a top guide device for sliding panel construction whereby the top portion of a slid- able panel is resiliently and yieldably laterally centered within a groove in the head of a framed opening to be closed.

A further object of this invention is to design and provide a top guide and spacing device for slidable panels wherein sliding movement of the

2

panel is accurately guided with virtually uniform clearance on opposite sides thereof to avoid unequal wear upon weather stripping material carried by the door.

5 Still another object of this invention is to present a top guide and spacing device for slidable doors, windows, panels, etc., which is easily manufactured, inexpensive, and simply installed.

Generally speaking, the top guide device contemplated by this invention includes a rectangular metal plate capable of being secured to the top edge face of a panel, door, or window. The plate may pivotally carry a pair of normally parallel arms disposed along diagonally opposite longitudinal edge portions of the plate. The inner ends of said arms may be transversely opposed and each inner end carries a roller or wheel mounted for rotation about a vertical axis, each wheel normally extending beyond the longitudinal edge of said plate and adapted to roll along interior wall surfaces of a downwardly groove formed in the head member of a door or window frame. The opposite outer end of each pivoted arm is connected to one end of a coil tension spring, the other end of said spring being connected to the plate, said spring biasing the wheels outwardly into resilient yieldable engagement with the side walls of the groove.

10 The invention contemplates a modification of the guide device wherein the rollers are urged outwardly by a single compression spring anchored at its central portion to the plate.

15 Other objects and advantages of this invention will be readily apparent from the following description of the drawings:

20 Fig. 1 is a top view of a top guide device mounted on the top portion of a window panel which is received within a groove in a head member of a window frame.

25 Fig. 2 is a sectional view taken in the planes indicated by the line II—II of Fig. 1.

30 Fig. 3 is a perspective view of a top guide embodying this invention.

35 Fig. 4 is a top view of a different modification of a top guide device embodying this invention.

40 Fig. 5 is a sectional view taken in a transverse central plane indicated by line V—V of Fig. 4.

45 The exemplary embodiments of this invention in Figs. 1-4 inclusive illustrates a guide device for sliding panel construction as adapted to a metal window frame and sash. It is understood the guide device may be employed in similar manner to sliding doors, panels, etc. mounted in a wooden frame.

50 In Figs. 1 and 2 a head, generally indicated

at 10, of a frame structure of a window opening includes a laterally extending downwardly facing groove or recess 11 having spaced internal side walls 12 and a top wall 13. The groove 11 receives therewithin a top transverse hollow member or rail 14 of a sliding window panel generally indicated at 15. The top rail 14 is illustrated as being formed of a metal box cross-sectional shape having a top wall 16. The top rail 14 includes a flanged inner portion 17 providing, in effect, a rabbeted inner edge margin for mounting a window glass 18. The window panel 15 includes a bottom transverse member or rail (not shown) which may carry a pair of guide-wheels which are cooperable with a suitable track on the sill of the frame for supporting the window panel in rolling guided contact with the track.

The top wall 16 of the top rail 14 carries on its upper face a ribbon or band of weather stripping material 19, said ribbon being of greater width than the spacing between side walls 12 of the groove so as to provide compressed bulbous longitudinally extending side portions 20 when the top portion of the window panel is received within groove 11. The ribbon of weather stripping material may be of any well known suitable type and may be secured to the top edge face of rail 14 in any suitable manner.

The top rail 14 is guided within groove 11 by a pair of top guide devices, generally indicated at 21, carried at opposite ends of rail 14, only one device being shown. Each top guide device 21 comprises an elongated rectangular flat metal plate 22 having parallel longitudinal edges 23. The width of plate 22 may be slightly less than the width of the top edge face of top rail 14. The guide 21 may be secured to rail 14 by securing screws 24 extending through the weather strip material 19 and into wall 16.

Plate 22 carries a pair of diagonally oppositely disposed normally parallel flat arms 25, each pivotally connected intermediate its ends at 26 to the plate adjacent to the transverse center line of the plate and to a longitudinal edge of the plate. The inner ends of arms 25 are oppositely disposed at the center portion of the plate. Each arm 25 carries a horizontally disposed wheel or roller 30, said roller being rotatable about a vertical axis, the diameter of said roller being greater than the width of arm 25.

Means for biasing each roller 30 outwardly beyond the adjacent longitudinal edge 23 of the plate 22 may comprise a tension coil spring 27 connected at one end to the outer end of arm 25 and anchored at its other end to an upstanding lug 28 formed at one side of each end of plate 22. The portion of the arm 25 extending outwardly from the pivotal connection 26 may be bent slightly upwardly for spacing said portion from the top surface of plate 22. In this arrangement of arms 25, rollers 30 are transversely oppositely disposed and each roller is biased outwardly for rolling contact as at 29 with the inner surface of side walls 12 of groove 11.

It will be readily apparent that a pair of such top guide devices attached to a top rail 14 of a window sash will resiliently and yieldably maintain the top portion of rail 14 within groove 11 in centered relation to the walls thereof and will provide virtually uniform equal clearance on opposite sides of the top portion of rail 14. Such resilient lateral maintenance of rail 14 in centered relationship within the groove 11 prevents rattling of the window sash in its slidable

mounting and at the same time permits the window sash to be easily slidable.

Such an arrangement also permits an effective and efficient disposition of weather stripping material on the top edge of rail 14. Since rail 14 is resiliently held in lateral spaced relationship within groove 11 and is accurately and uniformly guided therewithin, wear of said weather strip material will be substantially uniform throughout its length and will thereby effectively provide weather-tight protection for a maximum period of time.

In Fig. 4 a different modification of a top guide device is illustrated, this modification differing principally from the first embodiment described in that a single compression spring is employed instead of a pair of tension springs.

The top guide generally indicated at 35 comprises an elongated flat rectangular metal plate 36 adapted to be secured to a top edge face of a top rail of a window sash panel as by spaced screws 37. A pair of normally parallel arms 38 are each pivotally connected at one end as at 39 to plate 36. The opposite end of each arm 38 pivotally carries a horizontally disposed roller 40 mounted for rotation about a vertical axis and normally having a circumferential marginal portion projecting over a longitudinal edge of plate 36.

Means for biasing the arms 38, so as to urge the rollers outwardly into rolling contact as at 41 with side walls of a groove in a head of a frame structure defining an opening, is provided by a single compression spring 42 extending transversely of plate 36 at the central portion thereof. Each end of compression spring 42 is seated against an upstanding lug or abutment 43 suitably formed, as by stamping, out of the metal of arm 38. The abutment 43 may be provided withinwardly extending oppositely disposed side fingers 44 for holding the end of spring 42 against horizontal transverse movement and for defining a spring seat 45 for the end of the spring.

The center portion of spring 42 is held against lateral movement or deflection by means of an upstanding anchor member 46 suitably pressed out of the metal of the central portion of plate 36, said member 46 being provided with a downwardly facing hooked upper end 47. The hooked end 47 receives and holds a central coil of spring 42 against longitudinal movement when the compression spring is placed under compression, as when the guide device is mounted on a sliding panel within a groove as described above. The effect of anchor 46 is to separate the single compression spring 42 into two independently acting compression springs, each half of the spring 42 extending between anchor member 46 and an abutment 43 acting as a separate spring. The anchor 46 also holds the spring 42 against disassembly from the plate when the device is not in use and the spring is not under compression.

In both modifications described above it will be readily understood that lateral pressure against the sliding panel and transversely of the groove 11 will be resiliently and yieldably resisted by the spring means provided on each guide device and that as said pressure decreases or is released the guide device will resiliently urge the top portion of the panel back into virtually centered relationship within the groove 11. Each roller is biased outwardly independently of the other roller because of anchoring the spring means to the plate, and thus each spring acts to center

the top rail when placed under additional stress due to side forces acting against the panel. Thus wear upon the weather stripping material is substantially reduced and wear which does occur will be virtually uniform throughout the length of the ribbon of weather stripping material.

Since each of the top guide devices described acts to hold the top rail of a window sash member in centered relationship within the groove 10 the window sash is conveniently and easily movable into selected position without causing undue wear or unnecessary friction on the weather stripping material. Thus an improved mounting is provided for exterior installations where laterally slidable door, window or panel constructions are desired.

It is understood by those skilled in the art that various modifications and changes may be made in the embodiments of the invention described above and all such changes and modifications coming within the scope of the appended claims are embraced thereby.

I claim:

1. A top guide device for sliding panel construction wherein a top portion of a panel is slidably accommodated within a downwardly facing recess and for maintaining said top portion in normally centered relation within said recess, the combination of: an elongated plate 30 adapted to be secured to the top portion of a slidable panel; spaced parallel longitudinally extending arms overlying spaced longitudinal edge margins of said plate and each having a pivotal connection to said plate; a rotatable roller carried at the end of each arm and spaced from the pivotal connection; an upstanding anchor carried by the plate centrally between said arms; an upwardly directed portion on each arm op-

25

posite to said anchor; and a single spring connected to said anchor intermediate its ends and to both said upwardly directed portions and adapted to urge said rollers into contact with internal walls of said recess.

2. A top guide device for sliding panel construction wherein a top portion of a panel is slidably accommodated within a downwardly facing recess and for maintaining said top portion in normally centered relation within said recess, the combination of: an elongated plate adapted to be secured to the top portion of a slidable panel; spaced parallel longitudinally extending arms overlying spaced longitudinal edge margins of said plate and each having a pivotal connection to said plate; a rotatable roller carried at the end of each arm and spaced from the pivotal connection; upstanding anchor means provided on the plate, an upwardly directed portion on each arm opposite to said anchor means; and spring means held by said anchor means and connected to said upwardly directed portions and adapted to urge said rollers into contact with internal walls of said recess.
